UNITED STATES PATENT OFFICE

HENRY CHARLES GILHAM, OF FERGUS, ONTARIO, CANADA

INSTRUMENT BOARD CLOCK SUPPORT

Application filed May 16, 1930. Serial No. 453,055.

This invention relates to improvements in instrument board clocks for motor vehicles and the like and more particularly to a device for converting a watch into an instrument board clock, as described in detail in the following specification and illustrated in the accompanying drawings, forming part of same.

The invention consists of the novel features pointed out broadly and specifically in the claims for novelty, following a brief description in detail of an acceptable form of the invention, as illustrated in the accompanying drawings.

The objects of this invention are to construct means whereby an ordinary watch may readily be converted, when used in conjunction therewith, into a very convenient and attractive instrument board clock; to devise an instrument board clock that may be installed and attached to any nonporous planed surface such as an instrument board or windshield glass on a motor vehicle, without any preliminary preparation, prior to the installation thereon; to produce an instrument board clock that may be installed or detached by anyone, without the use of tools; to so construct a device of this description, that it may be readily detached and carried about in the pocket if desired, to have it ready for instant use on another vehicle; to effect means, in such a clock, that it may be positioned in the most convenient place for the driver or the passengers therein, and generally to provide an instrument board clock, pleasing in design and workmanship, economical of manufacture and capable of accomplishing the aforesaid results and purposes.

40 Referring to the drawings—Figure 1 is a plan view of the invention installed.

Figure 2 is a side elevational view of Figure 1.

45 Figure 3 is a vertical sectional view taken on lines 3—3 in Figure 2.

Figure 4 is a horizontal sectional view of a rubber vacuum cup as used on this invention.

Figure 5 is a view in detail of part of the invention.

Figure 6 is a horizontal sectional view of a slightly modified form of the invention.

In the drawings like numerals of reference indicate the corresponding parts in the various figures throughout.

The numeral 10 indicates the main body of the invention. It is formed of a cylindrical portion 10a having recesses 11 and 12 at each end, respectively, and separated from each other by an inwardly extending wall 14 rigid with the cylindrical portion 10a. A centrally located opening 15 formed in the wall 14 joins the recesses 11 and 12. The recess 11 is shaped to receive and releasably retain a watch therein, as shown in the drawings at 20. It is to be noted here, that although I show a watch in the drawings, said watch is only complementary to the invention proper.

The wall 14 supports the back of the watch 20 and the cylindrical side walls of the recess 11, loosely engage the periphery of said watch 20.

An indentation or groove 17 is formed in the side walls of the recess 11 to receive the stem of the watch and to allow proper positioning of same in the recess 11. An inner peripheral groove 13 is formed in the wall of the recess 11 and adjacent the entrance thereto. A resilient retaining ring 18 split as at 18a, is adapted to seat in the groove 13 and to bear against the watch 20 as at 18b, thus effectively securing the watch in the recess 11 and preventing its displacement therefrom, without the removal of the ring 18.

To facilitate the positioning and removal of the ring 18 from the groove 13, I provide loops or knobs 19 at each end of the ring so that said ring may be grasped at the knobs between the thumb and fore-finger and compressed.

In the rear recess 12 a vertical pin 23 passing through holes 23a formed in the walls 10a, extends across the recess. A rubber vacuum cup 21 is mounted in the recess 12 by passing the pin 23 through an opening 22 formed in the rubber portion at the rear of the cup. A spacer 24 mounted on the pin 23, above the opening 22 serves to retain the cup in its proper position on the pin 23. The cup 21 is preferably formed with an extended portion 25 at the rear, adapted to extend through the opening 15 and press against the back of the watch 20 to overcome any vibration, in the recess 11, of said watch. Knobs or extensions 26 adapted to loosely engage the wall 14, to prevent vibration of the main body 10, may be formed at the rear of the cup 21 as shown in Figure 4.

In the operation of this invention, the ring 18 is first removed from the groove 13 and the watch 20 placed in the recess 11 and positioned with the stem in the groove 17. The ring 18 is then replaced in the groove 13, care being taken to position the knobs in the groove 17, to prevent interference of said knobs with the inner periphery of the walls 10a. The device is now ready to be applied to any substantially nonporous surface as indicated at 27. This is accomplished by pressing the vacuum cup 21 against the surface 27 and bringing sufficient pressure to bear to force all the air from between said cup and said surface.

In the modified form of this invention, as illustrated in Figure 6, I show a slightly different method of attaching the vacuum cup 21 in the recess 12. Instead of using a pin, as at 23 in Figure 3, I extend the rubber portion 30 at the rear of the cup 21 to form a shoulder 31 adapted to snugly engage the inner periphery of the recess 12. An inner peripheral groove 33 is formed in the recess 12 and is positioned a short distance from the entrance to said recess. A flat resilient retaining ring is adapted to seat in the groove 33 and engage the shouldered portion 31, when same is positioned in said recess 12, to effectively secure said cup in said recess. The extension 25 is formed on the portion 30 and is adapted to extend through the opening 15 to bear against the back of a watch, as in the former case, shown above.

It is to be noted that I do not claim invention in relation to the rubber vacuum cup, such a device being used in various well known articles, but I do believe that such a device as described above, in its entirety is broadly novel.

What I claim is:

1. An instrument board clock support comprising a hollow cylindrical body, an inwardly extending annular ridge separating said body into two compartments, an inner peripheral groove in one of said compartments, a resilient ring split at one side and adapted

to seat in said peripheral groove and bear against a watch positioned in said compartment, a recess in the wall of said compartment adapted to receive the stem of said watch, and means in the other of said compartments for attaching a rubber vacuum cup therein.

2. An instrument board clock support comprising a hollow cylindrical body, an inwardly extending annular ridge in said body forming, on either side thereof, end recesses, an inner peripheral groove in one of said recesses, a resilient retaining ring split at one side and formed with finger-holds at the ends thereof, coacting means between said ring and groove and the walls of said recess for securing and releasably retaining a watch therebetween a groove in the wall of said recess adapted to receive the stem of said watch, and securing means, whereby the rear portion of a rubber vacuum cup, could be secured in the other of said recesses.

3. In an instrument board clock support, a hollow cylindrical body formed with respective recesses at either end communicating with each other by means of a centrally located opening, a split resilient retaining ring having outwardly extending knobs at the ends thereof, a peripheral groove in one of said recesses adapted to receive said ring, an indentation in the walls of said recess, a rubber vacuum cup formed with an annular ridge at the back thereof, adapted to form a snug fit with the side walls of the other of said recesses, a peripheral groove in said last named recess, a flat retaining ring adapted to seat in said groove and bear against the side of said annular ridge on said vacuum cup, and an extension formed on the back of said vacuum cup adapted to extend through said centrally located opening.

4. An instrument board clock support comprising a hollow cylindrical body, an inwardly extending annular ridge separating said body into two compartments, an inner peripheral groove in one of said compartments, a resilient ring split at one side and adapted to seat in said peripheral groove and bear against a watch positioned in said compartment, and means in the other compartment for attaching a rubber vacuum cup therein.

5. An instrument board clock support comprising a hollow cylindrical body, a divisional wall separating said body into compartments, said wall having an opening therein forming a communication between the compartments, an inner peripheral groove in one of said compartments, a split resilient ring seated in said groove so as to bear against a watch positioned in the grooved compartment with its back supported by the aforesaid wall, and a rubber vacuum cup attached in the other compartment and having its rear portion projecting through the wall open-

ing to bear against the watch to prevent its vibration.

6. An instrument board clock support comprising a cylindrical body recessed at both ends, a watch secured in one of the recesses, a peripheral groove formed in the other recess, a rubber vacuum cup formed with an annular ridge at the back thereof adapted to snugly fit within the grooved recess, and a flat retaining ring seated in said groove and engaged with said ridge to retain the vacuum cup in the recess.
